UNITED STATES PATENT OFFICE.

VINTON E. SISSON, OF CHICAGO, ILLINOIS, ASSIGNOR TO WALTER P. MURPHY, OF CHICAGO, ILLINOIS.

END CONSTRUCTION FOR RAILWAY-CARS.

1,342,604.

Specification of Letters Patent.

Patented June 8, 1920.

Application filed May 10, 1916. Serial No. 96,584.

To all whom it may concern:

Be it known that I, VINTON E. SISSON, a citizen of the United States, residing at Chicago, in the county of Cook and State 5 of Illinois, have invented certain new and useful Improvements in End Constructions for Railway-Cars, of which the following is a specification.

My invention relates to sheet metal ends 10 for railway cars, particularly box cars, designed to take the place of the ordinary wooden end sheathings either in new cars or in the repair of old cars, the end walls of which, particularly when of wood, are 15 frequently broken out by shifting cargoes so as to require replacement.

One of the objects of the invention is to provide a sheet metal end for a railway box car in which the lower part of the end is so 20 constructed that it is possible, without sacrificing strength, to omit the usual end sill, which, if of metal, adds materially to the weight of the car and the expense of its construction.

25 A further object of the invention is to provide certain novel arrangements for securely uniting the end sheets of the car to the end framing and joining together the elements of the end framing and under 30 frame of the car whereby the end of the car as a whole will be very strong, rigid and durable so as to be capable of withstanding the inertia thrusts of the cargo, weaving stresses and such other shocks and 35 stresses to which this part of a box car is subjected when in service.

The invention consists of the several 40 novel and improved constructions, arrangements and devices to be hereinafter described and claimed for carrying out the above stated objects and such other objects as will appear from the following description.

The invention is illustrated in certain 45 preferred embodiments in the accompanying drawings, wherein

Figure 1 is a fragmentary front elevation of a railway box car, in which the end structure is constructed in accordance with 50 my invention.

Fig. 2 is a sectional plan taken on line 2—2 of Fig. 1 with the flooring, side sheathing and other parts omitted.

Figs. 3 and 4 are vertical sectional views

taken on line 3—3 and 4—4, respectively, 55 of Fig. 1.

Fig. 5 is a fragmentary sectional plan taken on line 5—5 of Fig. 1 illustrating the preferred manner of securing the end sheet to the side wall. 60

Fig. 6 is a front view, in elevation, of another embodiment of my invention.

Fig. 7 is a sectional plan taken on line 7—7 of Fig. 6 illustrating the manner of securing the end sheet to the under frame 65 and to the metal corner posts.

Fig. 8 is a skeleton view, in perspective, of the upper portion of the end plate.

Fig. 9 is a fragmentary vertical section taken on line 9—9 of Fig. 6, the same being 70 drawn on a larger scale.

Figs. 10, 11 and 12 are angular attaching members employed in the construction shown in Figs. 6 to 9 inclusive.

Fig. 13 is a fragmentary front view, in 75 elevation, of another embodiment.

Fig. 14 is a sectional plan taken on line 14—14 of Fig. 13.

Fig. 15 is a vertical section on line 15—15 of Fig. 13, and 80

Fig. 16 is a fragmentary sectional plan taken on line 16—16 of Fig. 13.

Like characters of reference indicate like parts in the several figures of the drawings.

Referring first to Figs. 1 to 5, inclusive, 85 of the drawings, 10 designates the draft sills of a car which are here shown as being formed of ordinary commercial steel, Z-shaped in cross section, and 11 designates channel shaped side sills. The draft sills 90 are secured to an angular member 13 which extends from side to side of the car and has its horizontal flange 14 riveted or otherwise secured to the upper flanges 15 and 16 of the draft and side sills, respectively. Angular 95 members 17 are arranged below the angular attaching member 13 and are secured at their ends to the vertical webs of the said draft and side sills by means of angular gusset members 19, 20. The end sheet 21 is 100 preferably formed with horizontal pressed corrugations 22 which terminate within the edges of the sheet so as to provide flat surfaces 23 adjacent said edges. The vertical edges of the sheet are bent at right angles 105 to the main portion of the sheet so as to form angular attaching flanges 24 which are secured to the corner posts 25 by means

of bolts 26. The upper edge of the end sheet may be secured to the end plate or upper portion of the framing of the car in any suitable manner. This part of the 5 structure has been omitted in the drawings of this embodiment of the invention. The lower edge of the sheet 21 extends below the flooring of the car and is cut away, as indicated at 27, so as to fit over the draft 10 sills 10 and is secured to the vertical flanges 28 and 29 of the angular attaching member and braces 13, 17, respectively, by a double row of rivets 30, 31. The lower edges of the flanges 24 are riveted to the outer surfaces of said side sills. 32 is a short angle riveted to the end sheet and to the draft sills. The buffer casing 33 is secured to the draft sills and to angle 32.

With a car end constructed as above described, it is possible, without sacrificing strength, to entirely omit the ordinary end sill. The lower part of the lower end sheet is stiffened and rigidified so that an end sill is not required. The saving in expense 25 of construction is considerable. There is also a saving in weight which is an important consideration in a freight car. The draft sills are firmly attached to the lower end sheet. The end sheet serves as a plate 30 girder with respect to the vertical stresses exerted on the body of the car by the draft rigging. The horizontal disposition of the corrugations adds considerably to the strength of the sheet as against such stresses. 35 The reinforcing angles 13 and 17 stiffen and strengthen the bottom of the sheet as against the stresses exerted by the draft rigging, longitudinally of the car. The draft sills are connected to the end sheet and its 40 reinforcing angles and the latter are firmly united with the frame members at the sides of the car so that a structure is provided that is extremely strong and rigid and at the same time very light in weight. The 45 end sill of a box car of ordinary construction has to be made very strong, and consequently heavy, because it has to take care of the up and down stresses of the draft rigging as well as the thrusts and pressures in drafting and buffing. For this reason it has 50 been customary to employ cast steel or pressed steel end sills which, besides being relatively expensive, add considerably to the weight of the car. By employing a steel 55 horizontally corrugated end sheet this element will be sufficiently strong to take care of the up and down stresses. The transverse reinforcing members need be made only heavy enough to resist the thrusts and 60 pressures fore and aft of the car.

34 designates the end lining which is secured to nailing strips 35 arranged in the recesses formed by the corrugations, and to the flooring 36.

65 In Figs. 6 to 12 inclusive, I have illus-

trated another embodiment of my invention, in which the side plates, end plates and corner posts are made of steel instead of being made of wood, as illustrated in the preceding five figures. In this construction the 70 upper framework can be made very rigid and presents certain novel features in the construction which will be apparent from the following description: 10^a designates the draft sills, 11^a the side sills, 37 the corner 75 posts, 38 the end plates and 39 the side plates of the car. The corner posts are preferably angular in cross section and are secured with rivets 40 at their lower ends to the vertical webs of the side sills 11^a. The upper 80 ends are offset, as shown at 41, so as to extend inside the side plates 39, and are riveted to the vertical web of said plates and to the inner surface of the depending flange 42 of the end plate 38. The side plates 39 85 are preferably Z-shaped in cross section, and are further secured to the corner posts by means of the angular gussets 43 which are riveted to the corner post and to the lower horizontal flange 44 of the side plate. 90 A diagonally extending brace 45 is secured to the upper flange of the side plate and to the horizontal web of the end plate 38. I have shown the end as composed of two metal sheets 46 and 47, the upper one of 95 which overlaps the lower sheet near the middle of the car so as to provide a water tight joint. The sheets are preferably formed with horizontal pressed corrugations 48 which terminate within the edges of the 100 sheet so as to provide flat marginal portions 49 which are secured to the inner surfaces of the angular corner posts 37. By the use of the angular corner posts the inwardly projecting corrugations can be made 105 longer, that is, so that they extend closer to the edge of the sheet than is possible in a construction where an ordinary wood corner post is used. The upper edge of the sheet is secured to the inner surface of the flange 110 42 of the end plate 38. Located intermediate the draft and side sills are sills 50 which support the flooring 50^a. These sills are preferably Z-shaped in cross section and arranged so that their upper edge aligns with 115 the upper edge of the side sills, such position being a short distance above the upper edge of the draft sills. An angular reinforcing and stiffening member 51 for the lower edge of the end sheet 46 extends from 120 side to side of the car and is so arranged that its downwardly extending flange 52 overlaps the ends of the side, intermediate, and draft sills, the upper edge of the draft sills being cut away, as indicated at 53, to 125 permit such an arrangement. The horizontal flange of the angular member 51 is riveted to the upper flanges of the side and intermediate sills and to the upper flanges of the Z-shaped draft sills 10^a through filler 130

blocks 54 (Fig. 9). The lower edge of the end sheet 46 is riveted to the depending flange 52 of the angular attaching member 51. The connection between the sills of the car and the attaching member 51 is further strengthened and rigidified by angular gusset members 55, 56 and 57. The angular members 57 are particularly designed to prevent any outward spreading of the draft sills. Any tendency the draft sills may have to move inwardly is resisted by the position of the buffer casting 58 which is positioned between the draft sills and secured to the inner surfaces of the vertical webs of said sills by means of rivets 59. The buffer casting shown in this embodiment is provided with an integral flange 60 which is secured to the end sheet 46 and attaching member 51.

In Figs. 13 to 16, inclusive, I have shown another embodiment of my invention. The upper portion of the structure shown in these figures has been omitted from the drawings, as this structure may be substantially the same as that shown in Figs. 6 to 12, inclusive. In this construction, in order to insure a waterproof joint, I have shown an insert 61 of soft material, preferably tar paper, between the attaching surfaces of the sheet 46^a and the corner posts 37^a. The angular attaching member 51^a is riveted to the upper flange of the draft sills, as shown at 62 (Fig. 14), and to the lower flange of the intermediate sills 50^a as indicated at 63 (Fig. 14). The ends of the attaching member are secured to the vertical webs of the side sills 11^b by means of the angular gusset members 64. 65 designates rivets which secure the lower edge of the sheet 46^a to the vertical flange 52^a of the angular attaching member. 66 designates diagonal bracing members preferably T-shaped in cross section, which are secured to the member 51^a and to the intermediate sills 50^a. The draft sills 10^b are braced against outward spreading by means of bracing elements 67 which are angular in cross section and extend diagonally from the lower edge of said draft sills to the angular member 51^a. The buffer casting 68 is preferably formed with an inverted U-shaped attaching lug which extends between the draft sills and is secured to the horizontal flange of the angular member 51^a. The upper flanges of the vertical webs of the intermediate sills 50^a are preferably cut away, as indicated at 70, to permit the nailing strip 71 to be firmly seated on the horizontal flange of the attaching member 51^a (Figs. 14 and 15).

While I have shown and described my invention in certain preferred constructions, it will be understood that modifications other than those suggested might be made without departure from my invention.

Therefore I do not wish to limit myself to the exact structure shown and described, except so far as specific limitations may appear in the appended claims.

I claim:

1. In combination with the draft sills and side sills of a railway car, of a metal end sheet formed with pressed, horizontally disposed strengthening corrugations and provided at its lower end with an angular member for attaching the end sheet to the underframing of the car, and a rigidifying member secured to the lower portion of said sheet, extending from side to side of the car and attached to said side and draft sills.

2. In combination with the draft sills and side sills of a railway car, of a metal end sheet formed with pressed strengthening corrugations providing beams extending from side to side of the car and adapted to resist vertical stresses and to transmit buffing strains to the side wall of the car, a rigidifying member secured to the lower portion of said sheet, extending from side to side of the car and attached to said side and draft sills, and reinforcing and bracing members between the draft sills and the side sills, secured at their extremities to said sills and at intermediate points to said end sheet.

3. In combination with the draft sills and side sills of a railway car, of a metal end sheet formed with pressed, horizontally disposed strengthening corrugations providing beams extending from side to side of the car and adapted to resist vertical stresses and to transmit buffing strains to the side wall of the car, a rigidifying member secured to the lower portion of said sheet, extending from side to side of the car and attached to said side and draft sills, and reinforcing members between the draft sills and the side sills, secured at their extremities to said sills and at intermediate points to said end sheet.

4. In combination with the draft sills and side sills of a railway car, of a metal end sheet formed with pressed strengthening and rigidifying ribs providing beams which extend from side to side of the car and provided with a flat portion adjacent the lower margin thereof, an angular rigidifying member secured to the said flat portion of said sheet, extending across the car from side to side and attached to said side and draft sills, and angular reinforcing members between said draft sills and side sills secured at their extremities to said sills and at intermediate points to the lower marginal portion of said end sheet.

5. The combination with the draft sills and side sills of a railway car, of a metal end sheet formed with pressed strengthening corrugations providing a beam for resisting

the vertical stresses and for transmitting buffing strains to the side framing of the car and angular reinforcing members secured to the lower edge of said end sheet and 5 interposed between and secured at their extremities to said draft and side sills.

6. The combination with the draft sills and side sills of a railway car, of a metal end sheet formed with pressed strengthening 10 corrugations extending from side to side of the car and with a flat marginal portion at the lower edge thereof extending below the upper edges of said sills, horizontally disposed, and angular reinforcing members secured 15 to the lower edge of said end sheet and interposed between and secured at their extremities to said draft and side sills.

7. In combination with the draft sills, 20 side sills and side framing of a railway car, of a metal end sheet provided with pressed strengthening and rigidifying ribs extending from side to side of the car, and with vertical marginal parts for attaching said sheet to said side framing, the lower portion 25 of said sheet being cut away so as to fit over said draft sills, and means at the lower edges of the sheet for rigidifying the same and securing it to the draft and side sills.

8. In combination with the draft sills and 30 side framing of a railway car, of a metal end sheet provided with pressed strengthening and rigidifying ribs which extend from side to side of the car, adapted to resist vertical stresses and to transmit buffing 35 strains to the side framing of the car and with vertical marginal parts for attaching said sheet to said side framing, the lower edge of said sheet being cut away so as to fit over said draft sills, and separate reinforcing 40 members intervening between the draft and side framing of the car and secured to the same and to the lower edges of the end sheet.

9. In combination with the draft sills and 45 side framing of a railway car, of a metal end sheet provided with pressed strengthening and rigidifying ribs which extend from side to side of the car, adapted to resist vertical stresses and to transmit buffing strains 50 to the side framing of the car and with vertical marginal parts for attaching said sheet to the side framing, the lower edge of said sheet being cut away so as to fit over the draft sills, reinforcing members secured 55 to the lower edges of the end sheet and intervening between the draft sills and side framing of the car, and angular gussets for securing said reinforcing members to said draft sills and side framing.

60 10. In an end construction for railway cars, the combination with the draft sills and side sills of the car, of an end plate, corner posts, an angular member extending across the car from side to side above and 65 secured to said side and draft sills, a pair

of angular members intervening between and secured at their ends to said draft sills and side sills, and an end sheet formed with pressed strengthening and rigidifying ribs providing beams which extend from side to side of the car, and adapted to transmit buffing strains to the side wall structure, and provided with attaching margins for securing said sheet to said angular members, corner posts and end plate. 75

11. In combination with the draft sills and side sills of a railway car, of a horizontally corrugated metal end sheet providing beams which extend from side to side of the car, and adapted to transmit buffing strains 80 to the side wall structure, an angular reinforcing member extending across the car from side to side on the inside of said end sheet and secured to the side sills of the car and to the draft sills, an angular reinforcing 85 member on the outside of said end sheet secured to said draft sills and to said first mentioned reinforcing member, and reinforcing members, angular in cross section, intervening between the draft sills and the 90 side sills and secured thereto at their extremities and at intervening points to said end sheet.

12. In combination with the draft sills and side sills of a railway car, of a horizontally corrugated metal end sheet providing beams which extend from side to side of the car, and adapted to transmit buffing strains to the side wall structure, an angular reinforcing member extending across the 100 car from side to side on the inside of said end sheet and secured to the side sills of the car and to the draft sills, an angular reinforcing member on the outside of said end sheet secured to said draft sills and to 105 said first mentioned reinforcing member, reinforcing members, angular in cross section, intervening between the draft sills and the side sills and secured thereto at their extremities and at intervening points to said 110 end sheet, and a buffer casting arranged between and secured to said draft sills.

13. In combination with the draft sills and side sills of a railway car, an angular member which extends from side to side of 115 the car and secured to said side and draft sills, a pair of angular bracing members disposed between said draft and side sills and secured thereto, a metal end sheet formed with pressed strengthening and 120 rigidifying ribs and provided with a flat marginal portion along its lower edge for attaching said sheet to all of said angular members and providing a plate girder extending from side to side of the car adapted 125 to resist vertical stress and to transmit strains adjacent the vertical center of the end to the side wall structure of the car.
